UNITED STATES PATENT OFFICE.

CHARLES C. BLAKE, OF BROOKLINE, MASSACHUSETTS, ASSIGNOR TO C. C. BLAKE, INCORPORATED, OF BOSTON, MASSACHUSETTS, A CORPORATION OF NEW YORK.

ROUNDING MACHINE.

Application filed February 9, 1921. Serial No. 443,582.

To all whom it may concern:

Be it known that I, CHARLES C. BLAKE, a citizen of the United States, residing at Brookline, in the county of Norfolk and State of Massachusetts, have invented certain Improvements in a Rounding Machine, of which the following description, in connection with the accompanying drawings, is a specification, like reference characters on the drawings indicating like parts in the several figures.

The present invention relates to machines for use in the manufacture of lasts and shoes, and more particularly to sole rounding machines.

The principal object of the present invention is to provide a novel construction and arrangement of devices for operating upon and for supporting the work whereby the rounding operation is performed in an accurate and reliable manner.

To the accomplishment of this object, and such others as will hereinafter appear, the features of the invention relate to certain devices, combinations and arrangements of parts hereinafter described and then set forth broadly and in detail in the appended claims which possess advantages readily apparent to those skilled in the art.

The various features of the present invention will be best understood from an inspection of the accompanying drawings illustrating the preferred embodiment of the invention as constructed for rounding an insole secured to a last bottom, in which

Figure 1 is a front elevation of the insole rounding machine;

Fig. 2 is a plan of the platen or work supporting table;

Fig. 3 is a diagrammatic plan illustrating the relation between the edge of the rounded insole and the guiding flange on the leader;

Fig. 4 is an elevation of the last having a rounded insole attached thereto;

Fig. 5 is a detail in elevation of the leader;

Fig. 6 is a plan of the inside guide; and

Fig. 7 is an elevation of the inside guide.

In the illustrated embodiment of the invention a roughly died-out insole 1 (Fig. 1) is secured to a last 2 which is jacked upon a work support 3 of the saddle and spindle type. The work support 3 is provided with runners 4 which slide on a platen or table 5 secured upon the upper end of a post 6 which is mounted for vertical movement in bear-

ings 7 formed in a bracket 8 on a column 9.

In order to feed the work support 3 over the table 5 and thus transfer the point of operation of the operating means around the insole, the work support 3 is mounted on a leader 12 (Figs. 1 and 5) provided with a guiding flange 13. As shown in Fig. 3 the projections of the edge of the bottom of the last at the sides thereof upon the plane of the leader coincide with the inside face of the guiding flange. At the toe the projections of the edge of the last bottom upon the plane of the leader fall within the guiding flange. This variation at the toe of the leader is for the accommodation of the toe-box which in a subsequent operation will be applied to the toe-end of the insole. When the upper having the toe-box within it is lasted to the edge face of the insole in accordance with the method of lasting practised by me the projections of the free edge of the upper upon the plane of the leader will coincide with the inside face of the guiding flange throughout its length. Stated in another way, the projections upon the plane of the leader of the outside edge of the toe-box secured in position on the toe of the insole will coincide with the guiding flange at the toe of the leader.

The leader is actuated to transfer the point of operation of the tool around the insole by a pinion 14 (Fig. 2) which engages rack teeth 15 (Figs. 1 and 5) formed on the exterior face of the guiding flange 13. The pinion 14 is secured to the upper end of a short shaft 16 which carries at its lower end a bevel gear 17 (Fig. 1) engaged with a similar gear 18. The bevel gear 18 is connected by a universal joint 19 to a short shaft 20 which is connected by a universal joint 21 to a shaft 22 journaled in the column 9. The shaft 22 carries a worm wheel 23 which meshes with a worm 24 on a shaft 25 also journaled in the column 9. The shaft 25 (Fig. 1) is driven from a short shaft 26, journaled in a bracket 27 on the base of the machine, by a belt 28 which passes over pulleys on the shafts 25 and 26, respectively.

In order to correct the relative position of the operating means and the insole during the transfer of the point of operation of the operating means around the insole to maintain the edge of the insole in proximity to the operating means in the line of feed the guiding flange 13 on the leader is engaged

- by a rotatably mounted pin 29 (Figs. 2, 3, 6 and 7) arranged to engage inside the flange and by guide rolls 30 and 31 (Fig. 2) arranged to engage outside the flange.
- 5 These guiding devices are mounted on supports secured to the bottom of the table 5 and are positioned above the table 5 through an opening 32 formed therein. The support for the pin 29 is a lever 33 one end of 10 which pivots at 34 and the other end of which slides in ways 35 secured to the bottom of the table 5. The lever 33 is swung to engage the guide pin 29 with the guiding flange 13 by a toggle 36 the links of which 15 are pivoted to the bottom of the table 5 and to the lever 33, respectively. When the toggle is made the pin 29 is locked in engagement with the inside face of the guiding flange. The toggle 36 is made or broken by 20 a handle 37 forming an extension of one of the links of the toggle.
- In order to hold the leader down upon the work table the exterior face of the guiding flange 13 is bevelled as shown at 38 (Fig. 5).
- 25 This bevelled surface is engaged by the frusto-conical guide rolls 30 and 31. With this construction the guides 29, 30 and 31 have a three-point contact with the guiding flange and thus act to swing the work laterally 30 during its feed about an axis coinciding with the point of operation of the operating means to correct the relative position of the operating means and the insole and thereby maintain the edge of the insole adjacent the 35 operating point in the line of feed. To enable the rolls 30 and 31 to engage the flange at all times without binding as they traverse the reverse curves of the flange at the shank and around the toe the guide rolls 30 and 40 40 31 are journaled on the free ends of links 39 and 40, respectively, the rear ends of which are pivoted to a lever 41 pivoted at 42 to the bottom of the table 5. The links 39 and 40 are also pivoted to links 43 and 44 pivoted to the bottom of the table 5. The 45 guide rolls 30 and 31 are thus supported for movement transversely of the feed of the leader exactly as if they were supported on a slide but without the frictional resistance 50 incident to the use of a slide. The rolls 30 and 31 are actuated in a direction to press them against the exterior face of the guiding flange 13 by means of a spring 45 (Fig. 2). At its free end the lever 41 is pivoted 55 to a block 46 which loosely receives a rod 47 pivoted at 48 beneath the table 5. The spring 45 is coiled around the rod 47 and is interposed between the block 46 and a shoulder 49 on the rod.
- 60 With this construction the spring 45 normally holds the guide rolls 30 and 31 in the inoperative position shown in Fig. 2. When the guiding flange 13 on the leader is interposed between the inside and outside guides 65 and the handle 37 is actuated in a direction

to lock the inside guide 29 against the flange, the outside rolls are pushed forward thus placing the spring 45 under compression. The spring 45 yields during the feed of the leader so that it exerts its maximum and minimum pressures when the rolls 30 and 31 are being transferred around the shank and toe of the leader, respectively. The lever 41, however, inversely transmits the pressure of the spring so that the rolls 30 and 31 are held with a greater pressure against the toe of the leader than they are held against the shank of the leader.

The tool for trimming the roughly die-cut insole to the edge of the last bottom 80 consists of a knife 50 (Fig. 1) which operates with an anvil or foot 51 mounted on a cradle 52, all of which have a construction and mode of operation identical with the knife, anvil and cradle illustrated and described in the patent to Blake, No. 1,340,520, granted May 18, 1920.

The knife 50 vibrates in a plane intersecting the edge of the last bottom at the sides thereof. In order to maintain the plane of the knife intersecting the edge of the last bottom during its transfer around the toe of the insole, notwithstanding the toe-box variation hereinbefore referred to, the leader 90 12 is moved on the table 5 to shift the insole supported from the leader transversely of the feed. The insole is shifted twice during the rounding operation, first to remove the tool from the path determined by the leader, and then to return the tool to said path. The knife is thus caused to traverse a detour at the toe of the insole coterminous with the path determined by the leader.

In order to shift the leader on the surface of the table 5 transversely of the feed, the roll 29 (Fig. 6) is eccentrically mounted, with relation to the axis about which the roll turns on the support 33, to provide a low face 53 and a high face 54. The low face 53 engages the inside face of the guiding flange during the transfer of the point of operation of the tool along the sides and around the heel of the work (Fig. 3), while the high face 54 engages the guiding flange during the transfer of the point of operation 100 of the tool around the toe of the work.

The low face of the roll is held in engagement with the guiding flange by a pair of pins 55 and 56, the points of which engage the flange and hold the roll from rotation on the support 33. The high face of the roll is held against the flange by a pair of pins 57 and 58.

In order to rotate the roll and thus shift the roll at the proper time to move the leader transversely of the feed to cause the tool to traverse the detour, the leader is provided with a pair of slots 60 and 61. As the leader is fed longitudinally in the direction of the arrow (Fig. 3) the pins 56 and 58 move into 110 115 120 125 130

the slots 60 and 61, respectively, whereupon the travelling leader rotates the roll 29 to bring the high face and the points of the pins 57 and 58 into engagement with the 5 guiding flange. This causes the roll to move the leader transversely of the feed against the tension of the spring 45, which removes the tool from the path determined by the leader and starts the tool along the detour. 10 The tool is returned to the path determined by the leader by a second pair of slots 62 and 63 in the leader (Fig. 3) which engage the pins 55 and 57, respectively, and rotate the roll 29 to return the low face 53 15 into engagement with the flange.

It will be apparent to those skilled in the art that instead of using two pins and two slots to rotate the roll a single pin and a single slot may be employed. But two pins 20 and two slots impart a uniform motion with considerable throw to the roll and their use is to be preferred as a single pin and a single slot would impart a harmonic motion with a small throw to the roll.

25 While the invention has been illustrated and described in connection with a machine for rounding insoles assembled on a last bottom, it will be apparent to those skilled in the art that many features of the invention may be employed in machines for making the last which supports the insole and also in machines for rounding the outsole, known as rough rounding and channelling machines.

30 What is claimed as new is:

1. The combination with an operating tool, of a shoe supporting jack, a leader secured thereto provided with a guiding flange, means for feeding the leader longitudinally, and means for swinging the leader laterally during its feed longitudinally comprising a pair of guides arranged to engage the outside face of the guiding flange and a rotatable eccentrically mounted guide arranged to engage the inside face of the guiding flange. 40

2. The combination with an operating tool, of a shoe supporting jack, a leader secured thereto provided with a guiding flange, means for feeding the leader longitudinally, means for swinging the leader laterally during its feed longitudinally comprising a pair of guides arranged to engage the outside face of the guiding flange and an eccentrically mounted guide arranged to engage the inside face of the guiding flange, and means for operating the eccentrically mounted guide to cause the low and high faces thereof to alternately engage the inside 50 face of the guiding flange.

3. The combination with an operating tool, of a shoe supporting jack, a leader secured thereto provided with a guiding flange, means for feeding the leader longitudinally, means for swinging the leader 55

laterally during its feed longitudinally comprising a pair of guides arranged to engage the outside face of the guiding flange, and an eccentrically mounted guide provided with a set of projecting pins arranged to engage the inside face of the guiding flange. 70

4. The combination with an operating tool, of a shoe supporting jack, a leader secured thereto provided with a guiding flange, means for feeding the leader longitudinally, means for swinging the leader laterally during its feed longitudinally comprising a pair of guides arranged to engage the outside face of the guiding flange, an eccentrically mounted guide provided with a set of projecting pins arranged to engage the inside face of the guiding flange, and means on the leader cooperating with the pins for operating the eccentrically mounted guide to cause the low and high faces thereof to alternately engage the inside face of the guiding flange. 80

5. The combination with an operating tool of a shoe supporting jack, a leader secured thereto provided with a guiding flange, means for feeding the leader longitudinally, means for swinging the leader laterally during its feed longitudinally comprising a pair of guides arranged to engage the outside face of the guiding flange, and a rotatable eccentrically mounted guide arranged to engage the inside face of the guiding flange, and two pairs of pins connected to the guide, one pair operating to hold the low face of the eccentrically mounted guide 90

in engagement with the guiding flange and the other pair operating to hold the high face of the eccentric guide in engagement with the guiding flange. 95

6. The combination with an operating tool of a shoe supporting jack, a leader secured thereto provided with a guiding flange, means for feeding the leader longitudinally, means for swinging the leader laterally during its feed longitudinally comprising a pair of guides arranged to engage the outside face of the guiding flange, a rotatable eccentrically mounted guide arranged to engage the inside face of the guiding flange, two pairs of pins connected to the guide, one pair operating to hold the low face of the eccentrically mounted guide 100

in engagement with the guiding flange and the other pair operating to hold the high face of the eccentrically mounted guide in engagement with the guiding flange, and means on the leader cooperating with two of the pins (one pin of each pair respectively) to rotate the guide to reverse the face with which the guide engages the flange. 115

7. A machine of the class described, having, in combination, an operating tool, a

table, a work support, means for correcting

the relative position of the tool and the sup-

port including a leader for guiding the tool through a predetermined path, and mechanism for shifting the leader on the surface of the table to cause the tool to traverse a 5 detour coterminous with said path.

8. A machine of the class described, having, in combination, an operating tool, a work support, a leader connected thereto, a table, means for feeding the leader over 10 the table to transfer the point of operation of the tool around the work, means for swinging the leader during a predetermined part of the travel of the tool around the work about an axis passing substantially 15 through the point of operation of the tool, and mechanism for shifting the leader on the table transversely of the feed of the leader to remove the point of operation of the tool from proximity to the axis about 20 which the leader swings.

9. A machine of the class described, having, in combination, an operating tool, a work support, a leader connected thereto, a table, means for feeding the leader over 25 the table to transfer the point of operation of the tool around the work, means for

swinging the leader during a predetermined part of the travel of the tool around the work about an axis passing substantially 30 through the point of operation of the tool, mechanism for shifting the leader on the table transversely of the feed of the leader first to remove the point of operation of the tool from proximity to the axis about which the leader swings and then to return the 35 point of operation of the tool to its normal position.

10. A machine of the class described, having, in combination, an operating tool, a table, a work support, a leader connected thereto, means for feeding the leader to transfer the point of operation of the tool along the work, means for swinging the leader laterally to maintain the edge of the work in the line of feed, and means for 40 shifting the leader on the surface of the table transversely of the feed during a predetermined part of the travel of the tool along the work.

In testimony whereof I have signed my 50 name to this specification.

CHARLES C. BLAKE.
